COUNTERSINKING MACHINE

James A. Roberts, Detroit, Mich., assignor to Chicago Pneumatic Tool Company, New York, N. Y., a corporation of New Jersey

Application September 10, 1940, Serial No. 356,163

12 Claims. (Cl. 153—21)

1

This invention relates to gripping and pulling machines adapted for use in metal working operations such as the forming of countersunk holes in sheet metal. One of the uses of the invention is for operation on sheet aluminum forming the skin covering on the wings and other parts of aircraft construction.

The machine of the invention has particular application as a means for preparing material for "flush riveting" operations, in which a rivet having a pre-formed flat head is inserted into the work through a countersunk hole in order that the outer end of the rivet may lie flush or even with the surface of the work. Preparatory to the riveting operation the countersunk holes are formed by pressing a metal working tool, or die, through aligned drill holes in the adjacent sheets to be joined. The practice heretofore followed of pushing the die through the work has an important disadvantage in that such a method requires that a rigid support be held against the work on the underside thereof, or that side opposite to the one against which the die holding tool is pressed. The rigid support is necessarily connected in some manner with the die holding tool, or must be manually held by one workman while the die is driven into the metal by another workman. When working on large areas, such as the wings of aircraft, it is impractical to connect the rigid support to the die holder, and the second of the above methods is generally unsatisfactory because of a lack of uniformity and required skill on the part of the workmen.

It is proposed by this invention to introduce a new method of countersinking wherein the die holder and rigid support are embodied in a single tool which is pressed against one side of the work and functions to pull, or draw, the die through or partly through the metal toward the stationary rigid support.

One object of the invention is to obtain a gripping and pulling machine of simple and rugged construction which may be used in the forming of countersunk holes.

A further object is to insure positive gripping of the die before a pulling movement thereof may be effected.

A still further object is to place the gripping and pulling mechanisms under the control of a single control means.

Still another object is to enable countersunk holes of varying depth to be formed through the provision of an adjustable limit pin determining the distance which the die may be inserted

2

into the die holder, prior to the gripping and pulling operation.

The invention, in the embodiment herein disclosed, takes the form of a portable pneumatic tool having independently operable gripping and pulling assemblies actuated in a determined sequence under the control of a manually operable throttle valve settable to a plurality of control positions.

10 Other objects and structural details of the invention will be more apparent from the following description when read in conjunction with the accompanying drawings, wherein:

Fig. 1 is a view partly in longitudinal section and partly in elevation of the tool of the invention;

Fig. 2 is a detail view, showing the throttle valve and the pressure fluid supply passages which it controls;

20 Figs. 3, 4 and 5 are detail views similar to Fig. 2, on a larger scale, showing the throttle valve in longitudinal section, and indicating the respective normal, intermediate, or partly actuated, and the fully actuated positions of the valve;

25 Figs. 6, 7 and 8 are detailed views, on a larger scale than Fig. 1, in longitudinal section, of the chuck mechanism of the tool as it appears during the several steps of a countersinking operation, Fig. 6 showing the die inserted in the chuck mechanism but not positively gripped thereby, Fig. 7 showing the parts following actuation of the gripping mechanism, and Fig. 8 showing the parts in fully actuated position at the end of the pulling stroke; and

30 Figs. 9 and 10 are detail views showing, respectively, a rivet inserted in a countersunk hole, and, the finished connection made by upsetting the inner end of the rivet.

As shown in Fig. 1, the main body of the tool 40 is cylindrical in shape and has separated front and rear compression chambers C—1 and C—2 formed therein. The stationary supporting elements comprising the body of the tool include front and rear end plates 15 and 16 and an intermediate plate 17 positioned between the end plates and acting to separate the chambers C—1 and C—2. Spacing rings 18 and 19, supported between the respective end plates 15 and 16 and the intermediate plate 17, complete the formation of the front and rear compression chambers. A plurality of tie rods 21 (one shown) extend between the end plates 15 and 16 and pass through the intermediate plate 17 to hold the assembly in a fixed relationship. The rear end plate 16 has 50 secured thereto a pipe section 22 which serves as

a handle by which the tool may be supported. The front end plate 15 is formed with an outwardly facing boss 23 supporting a forwardly extending tubular element 24 which functions, in a manner later to be described, as a stationary die. Reciprocable within the chamber C-2 is a piston 25 having a rod 26 secured thereto and disposed co-axially of the tubular die 24. The rod 26 extends forwardly through the plates 17 and 15, passes through and beyond the boss 23, and terminates within the tubular die 24 near the outer end thereof. The front end of the piston rod 26 is formed with a circular recess 27 which is threaded and adapted to receive the threaded shank of a metal working tool in the form of a mandrel 28 (see Figs. 6, 7 and 8), inserted in the recess through the open outer end of the tubular die 24. When positively engaged in the recess 27, the mandrel 28 becomes, in effect, an extension of the rod, or tool holder, 26, and, upon rearward movement of the piston 25, is drawn into cooperative relation with the stationary die 24.

In using the tool to prepare two or more sheets of metal for riveting, the tool is held with the outer end of the die 24 pressed against one side of the work at a point substantially co-axial with a set of previously drilled aligned holes in the sheets. From the opposite side of the work the shank of the mandrel 28 is then passed through the aligned drill holes and inserted into the recess 27. Then when operation of the tool is initiated and the piston 25 begins to move rearwardly, the head 28a of the mandrel is drawn into engagement with the metal sheets and continued movement of the piston causes the mandrel to effect a countersinking action by forcing inward that portion of each sheet lying within the periphery of the die 24. The working end of the die 24 is formed with an inwardly tapered surface 29 which cooperates with the head 28a in the forming of the countersunk hole.

To facilitate reception and gripping of the mandrel 28, the front end of the piston rod 26 is formed as a chuck which has a slight radial resilience by reason of one or more longitudinal slots 31, formed therein. In the normal expanded position of the chuck (Figs. 1 and 6) the recess 27 is of such diameter as to receive the shank of the mandrel 28 with a clearance space preventing positive engagement of the complementary threaded portions on the mandrel and recess wall. To effect such positive engagement, the chuck-like end of the piston rod 26 is compressed, as a part of each countersinking operation, to the gripping position of Fig. 7. The means for pressing the outer end of rod 26 into gripping position comprises a sleeve 32 encircling the rod for a greater portion of its length and having a sliding fit therewith. The sleeve 32 lies between the piston rod 26 and the tubular die 24 and extends rearwardly into the compression chamber C-1 where it is secured to a reciprocable piston 33. The piston 33 is similar in size and general contour to the piston 25 and is capable of independent operation to effect movement of the sleeve 32 relatively to the piston rod 26. The front end of the sleeve 32 is formed with an inclined surface 34 cooperative with a complementary surface 35 on the front end of the rod 26. Upon actuation of the piston 33, the sleeve 32 is drawn rearwardly, relatively to the tool holder rod 26, and, through the co-action of the inclined surfaces 34 and 35, contracts the chuck-like outer end of rod 26 from the expanded position of Fig. 6 to the

gripping position of Fig. 7. Following the operation of the piston 33 the piston 25 may be actuated to pull the rod 26 and mandrel 28 through a working stroke.

The pistons 25 and 33 are driven through their working, or power, strokes by compressed air delivered to the chambers C-1 and C-2 under the control of a throttle valve, adapted, in one position, to admit air only to the chamber C-1, and, in another position, to admit air to both chambers C-1 and C-2. The pistons are held in the normal position of Fig. 1 by respective yielding means which act to return the pistons forwardly at the end of the power stroke. The yielding means associated with the piston 33 is a coil spring 36 arranged within the chamber C-1 between the rear face of the piston and the stationary plate 17. A similar spring may be used to return the piston 25 but a preferred construction is disclosed in which compressed air is used to exert a constant forwardly acting pressure on this piston. As shown in Fig. 1, the rear end plate 16 is recessed to form a chamber 37 in which a piston 38 is positioned. The piston 38 is of a reduced diameter with respect to the piston 25 and is secured to a rearward extension of the piston rod 26. The pistons 25 and 38 and rod 26 thus constitute an assembly reciprocable as a unit. One end of the previously mentioned pipe section 27 projects into the chamber 37 while the other, or outer, end is adapted for connection with a pressure fluid supply line (not shown) leading from a source of compressed air. Thus live air is directed constantly to the chamber 37 where it acts on the rear face of the piston 38 to urge the assembly comprising elements 25, 26 and 38 to the normal position of Fig. 1.

Considering now the means for conducting pressure fluid to the chambers C-1 and C-2 and for controlling the flow of such fluid, there is provided in the front end plate 15 a passageway 39 and in the stationary plate 17 a passageway 41, the two passageways opening respectively into the chamber C-1 and the chamber C-2 at the front ends thereof. Respective conduits 42 and 43 are connected to the passageways 39 and 41 and communicate with passages 44 and 45 extending from a bore 46 (Fig. 2) in the rear end plate 16. The bore 46 lies near the chamber 37 and is supplied with live air from the chamber through a connecting passageway 47.

Referring to Fig. 2, a throttle valve 48, of the piston type, is positioned in the bore 46 and is reciprocable vertically, under the control of an operating lever 49, to connect the passages 44 and 45 alternatively to the source of live air and to exhaust. The valve 48 is movable within a bushing 51 and has a head 52 lying below the lower end of the bushing and engageable therewith to prevent the flow of air from the lower end of the bore upward to the passages 44 and 45. A compression spring 53, interposed between the head 52 and a cap 54 closing the lower end of the bore 46, presses the valve 48 toward closed position. Referring also to Figs. 3, 4 and 5, it will be seen that the upper or stem portion of the valve 48 is hollow and is formed with three sets of ports 55, 56 and 57, permitting a flow of air to and from the interior of the valve. In the normal closed position of the valve (Figs. 2 and 3) the set of ports 55 lies outside the bore 46, above the bushing 51, and so opens the chamber within the valve to atmosphere. The sets of ports 56 and 57 are normally positioned opposite respective bushing grooves 58 and 59 communi-

cating with the respective passageways 44 and 45 through registering ports 61 and 62. The passageways 44 and 45 and their respective associated chambers C-1 and C-2 are thereby normally connected to exhaust, the air being free to flow from the chambers to the interior of the valve 48 and out to atmosphere through the ports 55. The groove 59, in bushing 51, is actually a counterbore extending through the lower end of the bushing and adapted to receive, with a sliding fit, a collar 63 formed on the valve 48 between the head 52 and the set of ports 51. The collar 63 functions to prevent the flow of air from the groove 59 through the ports 51 until the valve 48 is depressed a distance sufficient to place the ports 55 below the upper end of the bushing 51.

In initiating operation of the tool the valve 48 is first depressed from the normal position of Fig. 3 to the intermediate position of Fig. 4. This movement serves to unseat the valve head 52 and to place the collar 63 below the lower end of the bushing 51. Live air is then free to flow into the groove 59 and out port 62 to the passageway 44 where it is directed to chamber C-1 to actuate the piston 33. Air may also flow from groove 59 to the interior of valve 48 at this time but cannot escape therefrom since the sets of ports 55 and 56 lie out of registry with the bushing grooves and hence are closed. When the piston 33 has been moved rearwardly sufficiently far to complete the mandrel gripping portion of the operation, the valve 48 is depressed from the intermediate position of Fig. 4 to the fully actuated position of Fig. 5. As a result of this additional movement the set of ports 55 is brought from its previous position above the groove 58 downward into registry with this groove and thereby establishes communication between the passageway 45, leading to chamber C-2, and the interior of the valve 48. In this position of the throttle valve, air is directed from the groove 59 into passageway 44 and also through the sets of ports 56 and 51 into valve 48 and out the ports 55 to the passageway 45. At this time, therefore, live air entering bore 46 may flow simultaneously into the passageways 44 and 45 and is admitted to both chambers C-1 and C-2. Both pistons 25 and 33 are thereby actuated and the entire gripping and pulling assembly is drawn rearwardly to complete the countersinking operation. The reaction of the air pressure on the plates 15 and 17 pushes the stationary die 24 forwardly and holds the front end firmly against the work. At the end of the power stroke the operating lever 49 may be released, whereupon the valve 48 will be returned to normal by spring 53, and the chambers C-1 and C-2 thereby opened to the atmosphere through the ports and passageways leading to exhaust ports 55.

In order that countersunk holes of varying depth may be formed, there is provided, in the recess 27 (Fig. 1), an adjustable limit pin 64 which determines the distance which mandrel 28 may be inserted into the recess. The pin 64 has a threaded engagement in the recess 27 and may be turned to cause it to occupy a deeper or more shallow position in the recess. Since the stroke of the piston rod 26 is constant a variance in the position of the mandrel head 28a with respect to the stationary die 24 will cause a greater or lesser penetration of the work by the mandrel. In Figs. 9 and 10 it is shown how a countersunk hole of the type formed by the present tool is used in driving rivets flush with the outer surface of the work. A rivet A having a flat countersunk head

B is inserted into the previously formed hole and the inner end of the rivet is upset by a suitable riveting tool to form a tight fitting head C on the inner side of the work. The head B lies entirely within the countersunk hole in the outer sheet of material.

The method of countersinking and flush riveting as herein described, which includes the step of inserting a countersinking tool through aligned holes in a pair of metal sheets, is claimed in applicant's divisional application, Serial No. 730,884, filed February 26, 1947.

What is claimed is:

1. A gripping and pulling assembly, the elements of which are disposed about a common longitudinal axis and include; a reciprocable tool holder having a radially resilient chuck at one end thereof, a reciprocable sleeve surmounting said tool holder and operative upon movement relative to said tool holder to contract said radially resilient chuck, and independently operable fluid pressure pistons for actuating said sleeve and said tool holder.

2. A gripping and pulling assembly, the elements of which are disposed about a common longitudinal axis, and include; a reciprocable tool holder having a radially resilient chuck at one end thereof, a reciprocable sleeve surmounting said tool holder and operative upon movement relative to said tool holder to contract said radially resilient chuck, a pair of pressure fluid operated pistons for actuating said tool holder and said sleeve, one of said pistons being secured to said tool holder and the other to said sleeve, and an additional pressure fluid operated piston secured to said tool holder.

3. In a gripping and pulling machine, the combination of a tool holder having a chuck at one end thereof and reciprocable through a power stroke and a return stroke, a reciprocable sleeve surmounting said tool holder and operative upon movement relative to said tool holder to impart a gripping action to said chuck, a pair of pressure fluid operated pistons for actuating said tool holder, means for supplying pressure fluid to one of said pair of pistons in a direction to effect a power stroke of said tool holder, and means for supplying pressure fluid to the other of said pair of pistons in a direction to effect a return stroke of said tool holder.

4. In a gripping and pulling machine, the combination of a reciprocable tool holder having a radially resilient chuck at one end thereof, a reciprocable sleeve surmounting said tool holder and operative upon movement relative to said tool holder to contract said radially resilient chuck, independently operable pressure responsive means for actuating said sleeve and said tool holder, means for supplying pressure fluid to said pressure responsive means, and a throttle valve controlling the supply of pressure fluid to said independent means, said valve acting when set in one position to admit pressure fluid to one only of said means and acting when set in another position to admit pressure fluid to both said means.

5. A power tool for countersinking metal sheets preparatory to riveting, comprising a die forming an integral part of the tool and adapted to be pressed against one side of the work with a central opening therein in registry with a drilled hole in the work, a removable die having a stem which is passed through the drilled hole from the opposite side of the work and inserted into said integral die, the adjacent faces of said dies lying on opposite sides of the work and being formed with

complementary surfaces one of which is concave and the other of which is convex, a chuck embodied in the tool for gripping the stem of said removable die following its insertion in said integral die, fluid pressure means for actuating said chuck into gripping engagement with said stem, and fluid pressure means for moving said chuck in a direction to pull said removable die toward the work and for applying simultaneously the reaction of said force to said integral die in a direction to press it toward the work, said dies being thereby squeezed together to form a dimple in the intermediate sheet or sheets constituting the work.

6. A power tool for countersinking metal sheets, comprising a motor housing in the form of a cylinder, tubular extensions of reduced cross-section projecting from the opposite ends of said cylinder, the rearward of said extensions serving as a handle for the tool and the forward of said extensions being adapted to be brought to position surrounding a drilled hole in the work, a die at the outer end of said forward extension and having a central opening adapted to register with the drilled hole, said die forming an integral part of the tool, a removable die on the side of the work opposite said integral die and engageable with the work while a stem thereof is passed through the drilled hole and inserted into the integral die, the adjacent faces of said dies lying on opposite sides of the work and being formed with complementary surfaces one of which is concave and the other of which is convex, a chuck reciprocable within said forward extension and operable to grip and pull the stem of said removable die, a fluid pressure operated piston within said cylinder and operatively connected to said chuck to effect operation thereof, means for introducing pressure fluid into said cylinder to actuate said piston and apply the reaction of such force to said integral die in a direction to press it against the work, said dies being thereby squeezed together to form a dimple in the intermediate sheet or sheets constituting the work, and a throttle valve controlling the flow of pressure fluid and mounted adjacent said handle for convenient manipulation by the hand of the operator.

7. A power tool for countersinking metal sheets, comprising a motor housing in the form of a cylinder, a tubular extension of reduced cross-section projecting forwardly from the cylinder and adapted to be brought to a position surrounding a drilled hole in the work, a die at the outer end of said forward extension and having a central opening adapted to register with the drilled hole, said die forming an integral part of the tool, a removable die on the side of the work opposite said integral die and engageable with the work while a stem thereof is passed through the drilled hole and inserted into said integral die, telescoping shafts longitudinally movable within said forward extension, the inner of which shafts constitutes gripping and pulling means cooperable with the stem of said removable die, the outer of said shafts functioning to press said gripping and pulling means into gripping engagement with said stem, first and second fluid pressure pistons aligned within said cylinder and operatively connected respectively to said outer and inner telescoping shafts, means partitioning said cylinder into front and rear piston chambers respectively accommodating the first and second said pistons, the inner of said shafts extending longitudinally through said first piston

75 chamber and said partitioning means into said second piston chamber, means for supplying pressure fluid to said piston chambers to effect operation of said pistons and apply the reaction of such force to said integral die in a direction to press it against the work, said dies being thereby squeezed together to form a dimple in the intermediate sheet or sheets constituting the work, and means for controlling such fluid supply to initiate operation of said pistons in a determined sequence.

8. A countersinking machine according to claim 1, characterized in that said integral die, said motor housing and the partitioning means therein are held against relative movement and so arranged that the reaction of the fluid pressure exerted upon said pistons tends to press said integral die against the work.

9. A countersinking machine according to claim 1, characterized in that said means for controlling the supply of pressure fluid to said piston chambers comprises a throttle valve settable to one position to prevent the passage of fluid to either of said chambers, settable to a second position to admit fluid only to said front piston chamber, and settable to a third position to admit fluid to both said chambers.

10. A power tool for countersinking metal sheets, comprising a die forming an integral part of the tool and adapted to be pressed against one side of the work with a central opening therein in registry with a drilled hole in the work, a removable die having a stem which is passed through the drilled hole and said integral die from the opposite side of the work, the adjacent faces of said dies lying on opposite sides of the work and being formed with complementary surfaces one of which is concave and the other of which is convex, a reciprocable chuck into which said stem is inserted following its passage through said integral die, means for initiating gripping and pulling motions of said chuck to draw said removable die toward the work, said means reacting in a direction to press said integral die toward the work, whereby said dies are squeezed together to form a dimple in the intermediate sheet or sheets constituting the work, and means applying a yielding pressure to said chuck to prevent a pulling motion thereof until in gripping engagement with the stem of said removable die.

11. A power tool for countersinking metal sheets preparatory to riveting, comprising a die forming an integral part of the tool and adapted to be pressed against one side of the work with a central opening therein in registry with a drilled hole in the work, a removable die having a stem which is passed through the drilled hole from the opposite side of the work and inserted into said integral die, the adjacent faces of said dies lying on opposite sides of the work and being formed with complementary surfaces one of which is concave and the other of which is convex, a chuck embodied in the tool for gripping the stem of said removable die following its insertion in said integral die, fluid pressure means for initiating gripping and pulling motions of said chuck to draw said removable die toward the work, said means reacting in a direction to press said integral die toward the work, whereby said dies are squeezed together to form a dimple in the intermediate sheet or sheets constituting the work, and fluid pressure control means adjustable manually from a normal position successively to partly actuated and to fully actuated

positions thereby to complete a countersinking operation in separate stages each initiated at the will of the operator.

12. A power tool for countersinking metal sheets, comprising a die forming an integral part of the tool and adapted to be pressed against one side of the work with a central opening therein in registry with a drilled hole in the work, a removable die having a stem which is passed through the drilled hole and said integral die from the opposite side of the work, the adjacent faces of said dies lying on opposite sides of the work, one of said die faces being frusto-conical and tapering towards the other die face, said other die face having a central recess surrounded by an annular shoulder adapted to abut against the metal sheet, a reciprocable chuck into which said stem is inserted following its passage through said integral die, means for initiating gripping and pulling motions of said chuck to draw said removable die toward the work, said means reacting in a direction to press said integral die toward the work, whereby said dies are squeezed together to form a dimple in the intermediate sheet or sheets constituting the work, and means applying a yielding pressure to said chuck to prevent a pulling motion thereof until in gripping engagement with the stem of said removable die.

Certificate of Correction

Patent No. 2,419,657.

April 29, 1947.

JAMES A. ROBERTS

It is hereby certified that errors appear in the printed specification of the above numbered patent requiring correction as follows: Column 8, line 13, claim 8, and line 20, claim 9, for the claim reference numeral "1" read 7; and that the said Letters Patent should be read with these corrections therein that the same may conform to the record of the case in the Patent Office.

Signed and sealed this 1st day of July, A. D. 1947.
